UNITED STATES PATENT OFFICE.

ANDREW R. LANDQUIST, OF MINNEAPOLIS, MINNESOTA.

SANDING MACHINE.

Application filed May 29, 1926. Serial No. 112,499.

This invention relates to a sanding machine particularly adapted for use in connection with the sanding of articles having surfaces thereon of varying heights and of varying curvatures such, for example, as school desks and seats, tables, chairs, etc.

It is an object of this invention to provide a sanding machine having a sanding belt therein mounted on a carriage which will be vertically adjustable to quickly position the working run of the sanding belt at various heights.

It is another object of the invention to provide in such a machine a counter-balanced carriage upon which the sanding belt is mounted.

These and other objects and advantages of the invention will more fully appear from the following description made in connection with the accompanying drawings in which like reference characters refer to the same or similar parts throughout the several views and in which

Fig. 1 is a view in front elevation of the device, certain of the parts being broken away;

Fig. 2 is a horizontal section taken on the line 2—2 of Fig. 1 as indicated by the arrows; and

Fig. 3 is a vertical section taken on the line 3—3 of Fig. 1 as indicated by the arrows.

Referring to the drawings, preferably a base 4 is provided having secured thereto the vertical standards 5 rectangularly spaced in relation to one another to form an upright frame preferably of greater length than width. The end standards 5 of the frame are transversely connected together at their tops by the bars 6 shown as I bars extending transversely of the frame. Facing inwardly from the ends of the frame, the tracks 7, shown as I bars, are provided secured to the standards 5 and extending substantially vertically. A carriage is provided comprising guide members 8, shown as inwardly flanged channel bars which slidably engage with tracks 7, and the bars 9, shown as channel bars, secured to the guide members 8 and extending longitudinally of the frame between the respective front and rear members 8. The ends of the carriage are connected together by suitable bracing 10 extending between the respective end guides while the angular braces 11 are preferably provided connected to the bars 9 and

to the guides 8 at spaced points. Bars 12, shown as angle bars, are secured to the bars 6 inwardly of the standards 5 and extend longitudinally of the frame formed by said standards at the top thereof.

Two bars 13 are fixed transversely between the bars 9 at the central portion of the carriage and form a seat upon which a motor 14 of any common type may be secured. The motor 14 has an elongated shaft projecting rearwardly therefrom upon which is mounted the pulley 15, the rear end of the shaft being journaled in the bearing 16 secured to the rear bar 9. Horizontal shafts 17 and 17^a are journaled in bearings 18 secured adjacent the lower ends of the guide members 8. An endless belt 19 placed over pulley 15 drives one of the shafts, as 17, through the pulley 20 secured on the shaft 75 opposite the pulley 15, the shaft accordingly forming the drive shaft for the machine. Sanding belt pulleys 21 are secured to shafts 17 and 17^a at their front ends forward of the front bearings 18. A shaft 22 journaled 80 in bearings 23 and 24, secured respectively to the front bar 9 and the bars 12, carries the pulley 25 thereon extending forwardly of the front bar 9 of the carriage and alined with the pulleys 21. A sanding belt 26 having an abrasive outer surface fits over the pulleys 21 and 25, the belt being loosely stretched over the pulleys. A bracket 27 extends downwardly from the front bar 9 of the carriage and has pivoted thereto the 90 arm 28 to one end of which in turn the pulley 29 is journaled, said arm 28 having the adjustable weight 30 secured thereto at its other end. Pulley 29 extends forwardly of arm 28 and is adapted to contact the inner side of the sanding belt 26, the pulley 29, arm 28 and weight 30 forming a belt tightener for the sanding belt.

Sheaves 31 are secured to the bars 6, preferably centrally thereof, and cables 32 running over the sheaves have their inner ends secured to eyes 33 mounted on the bracing 10, the other ends of the cables 32 having weights 34 secured thereto.

A steering wheel windlass is provided for 105 conveniently raising or lowering the carriage in the frame. Brackets 35 secured to the inner sides of the bars 9 and projecting downwardly therefrom have journaled therein the shaft 36 provided at its outer end 110 with the steering wheel 37 and having secured at its central portion the drum 38.

A cable 39 having its lower end secured to an eye in the base 4 and its upper end secured to a bar 40 extending transversely between the bars 14 is provided, said cable intermediate its ends being wound once or more around drum 38.

- Spaced tracks 41 are secured to base 4 below the carriage and at right angles to the sanding belt 26. A work holding platform 16 comprising a body portion 42, bearings 43, axles 44 and flanged wheels 45 secured at the outer ends of the axles 44, is placed on the tracks 41. A dust collecting casing 46 having the sliding door 47 at its lower extremity 15 is secured at the front side of a front standard 5 at the end of the frame towards which the working run of the sanding belt is directed when in operation. Casing 46 partially encompasses one of the pulleys 21.
- 20 Rotating tools as the sanding disk 48 secured to shaft 17 and the drill chuck 49 secured to shaft 17^a may be placed on the free ends of the shafts 17 and 17^a.

25

Operation.

- An article to be sanded is placed on the body portion 42 of the work holding platform and the platform is pushed inwardly on the tracks 41 towards the rear of the 30 frame until the portion of the surface of the article to be operated upon is placed directly below the sanding belt 26. The carriage is now slidably lowered by rotation of the steering wheel 37 of the steering wheel windlass 38 until the lower or working run of the belt 26 is positioned with its abrasive surface closely adjacent the surface of the article to be sanded, the guide members 8 of the carriage 40 sliding downwardly on the tracks 7 of the frame until this position is reached. The weights 34 will counter-balance the carriage so that the same will be capable of being quickly and readily moved as the drum of the steering wheel windlass is turned. The 45 motor 14 may now be started and power will be transmitted through the pulley 15, belt 19, pulley 20, shaft 17 and pulley 21 fixed on shaft 17 to the sanding belt 26. The sanding belt 26 will accordingly be rapidly rotated over the pulleys 21 and 25. An operator 50 may now stand in front of the article to be sanded and by a suitably shaped block (not shown) may hold the working run of the belt against the surface to be sanded. As the belt 26 fits loosely over the pulleys, the same 55 may be curved to fit the various curvatures of the article operated upon. The belt tightener comprising the members 28, 29 and 30 will properly tension the belt at all times 60 to prevent the same from slipping. By varying the position of the weight 30 on the arm 28, the tension of the belt tightener may be varied. The majority of dust from the sanding operation will be carried by the belt 65 26 to the dust collecting casing 46, the slid-

ing door 47 providing a handy means for removal of the dust from the casing 46. As the work progresses, the work-holding platform may be pushed to or from the belt as desired, to operate upon various portions of the surface of the article.

When it is desired to vary the vertical position of the working run of the sanding belt, as for example, when a surface of an article standing at a greater height or lesser 75 height than the surface being worked upon is to be operated upon, the windlass wheel 37 may again be revolved and the carriage and lower run of the sanding belt accordingly quickly raised or lowered through the 80 sliding engagement of the guide members 8 with the tracks 7 until the proper vertical level is reached.

As in the present invention all the operating mechanism for the sanding belt is mounted directly upon the sliding carriage, no adjustment of power transmission mechanism is necessary when the vertical position of the sanding belt is changed. The device can accordingly be quickly and easily raised 85 or lowered to properly position the sanding belt for engagement with articles of variable heights.

When the machine is not in use, the work-holding platform may be pushed inwardly 90 under the carriage to the position shown in Fig. 2 so that the platform will be out of the way. The sanding disk 48 and drill chuck 49 or other rotating tools that may be carried by the shafts 17 and 17^a will be found 100 convenient for use in connection with the other parts of the machine.

Various types of abrasive or polishing belts may be used in connection with the machine, the device being equally effective for 105 polishing articles as for sanding them. The specific type of belt tightener, steering wheel windlass, and counter-balancing means may be varied, while the positions of the motor, driving shaft and the sanding belt pulleys 110 may be changed as desired. The frame and carriage construction can also be considerably varied.

The device comprises few parts, is simple 115 in operation and may be comparatively cheaply made and assembled. The device has been amply demonstrated in actual practice and has been found to be very successful for the purposes set forth.

It will, of course, be understood that various 120 changes may be made in the form, details, arrangements and proportions of the parts without departing from the scope of applicants' invention which, generally stated, consists in the matter shown and described 125 and set forth in the appended claims.

What is claimed is:

1. A sanding machine having in combination, rectangularly spaced standards forming vertical tracks, a carriage slideable on said

tracks, a motor mounted on said carriage, a plurality of pulleys mounted for rotation on said carriage, means for driving one of said pulleys from said motor, an abrasive belt adapted to run over said pulleys, the lower run of said belt projecting downwardly from said carriage, means for counter-balancing said carriage to hold the same in any desired position or to permit the same being quickly shifted to different levels, and means for moving the carriage to any desired level.

2. The structure defined in claim 1, said last mentioned means comprising a cable secured at both ends to stationary supports and extending substantially vertically beside the carriage, and a drum journaled in said carriage and around which the medial portion of said cable is wound, the said drum being capable of being turned.

In testimony whereof I affix my signature.

ANDREW R. LANDQUIST.
